TYPEWRITER DESK

John H. Bushnell, Grand Rapids, Mich.

Application February 15, 1937, Serial No. 125,752

25 Claims. (CL. 312—26)

This invention relates to typewriter desks having a novel structure for attaining substantially the same results as in my Patent No. 2,066,608 issued January 5, 1937. Such results are attained in a different, better and a more practical manner by use of different structure.

In the present invention, as in my issued patent above identified, the novel construction provided permits the housing of a typewriter within one of the pedestals of an ordinary desk without increasing the width of the typewriter housing pedestal, or the over-all length of the desk and also substantially eliminates the previous drawer structure which at least has a partial bottom. 15 The present structure dispenses entirely with the bottom and also with the back and one side of the drawer so that there is no interference with the operator because of the partial bottom to the drawer structure which carries the typewriter in my earlier structure.

It is a further object of the present invention to provide a supporting means for the typewriter when it is to be used which may be first withdrawn from the desk pedestal and which at its outer end is supplied with retractile leg supports so that the support for carrying the weight of the typewriter is withdrawn from the desk pedestal and stabilized and held securely in position, adjusting said supporting legs before the typewriter is withdrawn and moved to operative position. This eliminates the strain which, in my prior structure, must be withstood by the drawer guides. It also eliminates any possibility of the desk being overbalanced toward the front. 25 In a complete two pedestal desk such overbalancing is not a serious danger, but where a typewriter desk alone is made of the usual 42" width, one pedestal being eliminated, the prior construction shown in my issued patent does not have enough desk weight to insure against forward tipping of the entire structure when the drawer with the typewriter therein is withdrawn. But with the present invention a typewriter desk of the standard 42" width, having one pedestal in which the typewriter and its carrying structure is mounted and within which it is housed when not in use, may be very practically produced, providing a typewriter desk which has a flat unbroken top which is not changed or altered in any way whether the typewriter is housed within the desk and out of use or is withdrawn therefrom and in use.

The present invention also has for an object the provision of a movable stationary receptacle which is connected to and movable with the im-

mediate typewriter table so as to follow it outwardly after it and the attached typewriter are moved outwardly toward operative position a pre-determined distance, and which is pushed back into the drawer pedestal when the typewriter is returned within the pedestal. With this construction there is little unused or waste space. With a two pedestal desk the ordinary standard length of 54" for the desk is ample, and with the typewriter desk wherein there is an elimination of one of the pedestals, a fully practical and very useful typewriter desk may be made within the standard 42" length for such desk and which will provide a full top surface of the desk at all times.

The invention is directed to many novel constructions and arrangements of parts for the attainment of the ends stated, as well as many others not enumerated, but which will appear in and be understood from the following description, taken in connection with the accompanying drawings, in which

Fig. 1 is a perspective view of a typewriter desk made in accordance with my invention and showing the typewriter in its position of use.

Fig. 2 is a longitudinal horizontal section through the desk pedestal in which the typewriter is to be housed, the plane of said section being a short distance below the top of the desk, showing the parts housed within the pedestal.

Fig. 3 is a view similar to Fig. 2 but with the parts extended outwardly substantially as they are in Fig. 1.

Fig. 4 is a vertical transverse section from front to rear through the same pedestal showing the parts partially extended outwardly.

Fig. 5 is a vertical section substantially on the plane of line 5—5 of Fig. 3, looking in the direction indicated by the arrows, and with the typewriter supporting shelf in raised position.

Fig. 6 is a vertical section substantially on the plane of line 6—6 of Fig. 3 looking rearwardly as indicated.

Fig. 7 is a perspective view of the typewriter supporting table or shelf and showing the locking or binding mechanism carried on the underside thereof, and

Figs. 8 and 9 are fragmentary enlarged vertical sections substantially on the planes of lines 8—8 and 9—9 of Fig. 3, in Fig. 9 the typewriter supporting table being turned to horizontal position.

Like reference characters refer to like parts in the different figures of the drawings.

The desk shown in Fig. 1 has a pedestal 1 at one end of the desk and a top 2 which extends

over said pedestal, the other pedestal to which my invention is applied and the space or well between the pedestals.

The pedestal of the desk to which my invention is applied has vertical corner posts 3, an inner side 4, an outer side 5 and a vertical back, as is usual, there being a horizontal bottom frame, having front and rear side bars 6 as shown located a distance above the lower ends of the 10 posts 3, this being conventional desk pedestal structure in which, at the open front thereof drawers are normally inserted, mounted upon any conventional drawer guides for ease of operation in withdrawing or retracting the drawers. 15 In my invention, at the uppermost part of said open front and underneath the top, a horizontal cross bar 7 (Fig. 4) is mounted between the front posts 3. The open front of this pedestal is closed by a vertically positioned front member 8, 20 the outer side of which may simulate a series of drawer fronts one over the other as shown. The member 8 is connected near one vertical edge to a vertical side member 9 which is adapted, when within the pedestal, to lie parallel to and adjacent 25 cent the outer side 5 of the pedestal. It is guided at its upper edge in a horizontal guide 10 and at its lower edge rides upon a side member 6 of the bottom frame previously described and held by a guide bar 11 (Fig. 6). The vertical 30 side member 9 with the attached front member 8 may thus be moved outwardly to the position shown in Fig. 1 or inwardly to the position shown in Fig. 2, in which latter case the upper edge portions of the front 8 come underneath the 35 lower edge of the bar 7, the same as the upper drawer in the pedestal 1 comes underneath a similar bar in such other pedestal.

The vertical side member 9 of the structure so far described, at its outer side lies closely adjacent the inner side of the adjacent corner posts 3 at the outer side of the pedestal. Such outer side 5 of the pedestal at its inside and immediately back of the front posts 3 has a block 12, 40 permanently secured and adjacent the rear of the side member 9 is a second block 13, the outlines of which are shown best in dotted lines in Fig. 4, said blocks 12 and 13 having complementary inclined lower and upper sides respectively. The block 13, coming underneath the block 12 at the outermost position of said side member 9, causes 45 the outer end of the side 9 and of the front member 8 attached thereto to be elevated or tilted upward a short distance and in effect wedged in such position. It will be noted that the side member 9 is tapered slightly at 50 to permit this 55 action. It will also be noted (referring to Fig. 6) that there is a lateral complementary inclination of the lower and upper edges of the blocks 12 and 13 such that the side member 9 is moved 60 into a snug engagement with the adjacent front post 3 when it is withdrawn to its outermost position. The outer side of the member 9 is preferably provided with felts indicated in Fig. 6 which press against the inner sides of the adjacent post 3 when at such outermost position.

The front 8, at its rear side and adjacent its free edge, carries a wood block 14 which may be of the form shown having a horizontal upper end on which a support 15 for the movable type- 70 writer carrying table or shelf is pivotally mounted. The support 15 is in the form of a U-shaped sheet metal channel having its flanges extending downwardly and coming one on each side of the block 14 whereby such support normally occupies 75 a horizontal position as shown in Figs. 3 and 4

but may be turned upwardly away from such position. Near the upper end of the front 8 and near its upper side is a pencil rack 16 and at the corner where the front 8 and the side 9 are joined together is a vertical reinforcing bar or post 17 which adds strength to the structure. 5

At the lower part of the front 8 and a distance above the lower edge thereof a horizontal cross bar 18 is permanently secured. A second horizontal bar 19, having legs 20 one at each end 10 thereof projecting at right angles, is hinged by hinges 21 to the lower edge of the bar 18 (Fig. 5).

A coiled spring 22 is connected at its ends to suitable pins one mounted on the bar 18 and the other on one of the legs 20. Said spring, when 15 the legs 20 are in the position shown in Fig. 4, tends to turn the same still farther upward in a counterclockwise direction. A stop 23 (Fig. 5) of metal attached to the bar 18, interposes a limit to the upward turning movement of said legs and 20 holds them in a substantially horizontal position. By turning the legs 20 in a clockwise direction the spring will pass across the pivotal axis of the 25 hinges 21 and will then tend to hold the legs in vertical position, as in Fig. 1, thereby providing a solid support for the lower end of and 30 extending downwardly from the front 8 and resting on the floor. The slight elevation of the front 8 when it, with the connected side 9, is withdrawn to its outermost position, due to the 35 engagement of the blocks 12 and 13, insures that the legs 20 will turn fully to their vertical position and not be tilted slightly forward of such vertical position at their lower ends, as might be the case if the front was not thus lifted. 35

At the inner side of the member 9 a horizontal narrow track 24 is permanently secured and above such track a length of flat sheet metal bar 25 is permanently secured and spaced from the side member 9 by an intervening bar 26 (Fig. 8) 40 of less width than the bar 25, the lower edge portions of the bar 25 extending below the lower edge of the bar 26. In the upper edge of the member 9 and at the inner side two spaced apart recesses 27 are mortised as shown. The functions of the track 24, the bar 25 and the recesses 27 will hereinafter appear. 45

A horizontally positioned tube 28 is mounted at its rear end on the back of the pedestal and at its front end is carried by a bracket 29 secured to the guide 10 (Fig. 6). A second tube or rod 30 telescopes into the tube 28 and at its front end is secured to the post 17, whereby on outward movement of the front 8 the tube 30 is drawn outwardly from the tube 28 in which it is received and into which it telescopes on the inward movement of said front. 55

A supporting table 31, on which the typewriter, indicated in dotted lines in Fig. 1, is to be secured, has rollers 32 connected thereto and projecting from a side thereof, said rollers being adapted to ride upon the tube 28 when the pedestal is closed by the front 8 and to ride upon the tube or rod 30 when the parts are moved to outer position, shown in Fig. 3. Such table and typewriter may be swung downwardly so that the table occupies a substantially vertical position as shown in Figs. 2 and 3; and when moved to outermost position as in Fig. 3, the table and typewriter may be swung up to the horizontal 70 position as in Fig. 1, whereupon the rollers 32 enter the recesses at 27, the table comes underneath the pivotal support 15 lifting it until the table has passed by the end of such support, whereupon the table is lowered to rest on the 75

support and be held in horizontal position with the typewriter ready for use. A block 33 is connected to the lower side of the table 31 and in a position such that when said table is lifted to horizontal position the block wedges between the side 9 and the tube 30 (Fig. 9) and holds the table against aimless movement. A clip 34 is also secured to the same side of the table 31 adjacent one of the rollers 32 whereby the rod 30 is between such roller and the clip and the table cannot accidentally be disconnected because of such construction. A flat metal plate 35 is attached to the table 31 at its forward edge and is adapted to be engaged by the hand for drawing the table with the typewriter secured thereon outwardly from the position such as shown in Fig. 4 to the outermost position in which it is to be turned upwardly and held as shown in Fig. 1. It is, of course, to be understood that the table 31 with the typewriter secured thereto does not move outwardly with the front 8 and side member 9, these having first been withdrawn and the supporting legs 20 turned to supporting position, after which table 31 is moved to outermost position.

A roller 36, connected to the underside of the table 31, traverses the track 24 as the table is moved outwardly. A Z-shaped clip 37 is also secured to the underside of the table and has its free end flange in a position such that it moves between the free edge of the bar 25 and the adjacent side member 9. Until this clip has passed by the front end of the bar 25 the table cannot be lifted to horizontal position, thereby preventing attempted elevation of the table until it has reached a predetermined outer location, and at which location, when it is lifted to horizontal, the rollers 32 will be received in the recesses 27.

40 A bar 38 is mounted for sliding movement in clips 39 therefor at the underside of the table 31 and has inclined ends as shown in Fig. 7. When the table is lifted to horizontal and brought down upon the pivoted support 15 the inner side 45 of said support rides upon the outer inclined end of the bar 38 moving the bar longitudinally and pressing its opposite inclined end against the rod or tube 30 thereby pinching said rod between the bar 38 and the other roller 32. This structure 50 operates automatically and, together with the wedge block at 33, securely holds the table against aimless movement, vibration or other undesired movements which might take place when the typewriter is being used, if such holding mechanism were not used.

55 A receptacle 40, having top and bottom, sides and back, but open at its front, is divided by means of partitions into several compartments and is mounted for movement at one side near its upper end by means of rollers 41 on the tube 28. At its other side and near its lower end rollers 42 carry the receptacle upon one of the side members 6 of the lower pedestal frame. A flat metal bar 43 extends along the side of the 60 receptacle 40 so as to serve as a support on which to mount the rollers 41 and at its front end is turned inwardly making an ear 44, which has an opening therethrough. A rod 45 headed at its rear end passes through the opening in the ear 44, and at its front end has a loose universal connection to an eye 46 which is secured to the rear edge of the table 31. In the length of the rod 45 is a shoulder 47.

70 After having moved out the front 8 and the 75 connected side member 9, and moving the sup-

porting legs 20 to operative position, the part 35 is grasped and the table 31 moved outwardly. At the beginning of such movement the rod 45 is located so that the shoulder at 47 is against the ear 44 (Fig. 2) whereby in the beginning there is outward movement only of the table 31 with the attached typewriter. When the rod 45 has progressed outwardly far enough that the head at its rear end engages with the ear 44 the receptacle 40 is pulled outwardly. At its foremost position, it has its open front substantially flush with the front side of the pedestal (Fig. 1). Envelopes, paper and the like are thereupon freely accessible for removal to be used in the typewriter. The receptacle 40 has a stop block 48 at its side (Figs. 2 and 3) which comes against a front post 3 (Fig. 3) when the forward movement of the table 31 has reached its desired limit.

A vertical sheet metal plate 49 is connected to the outer side member 6 of the lower pedestal frame and has its upper free end portion turned so as to lie in a plane inclined to the horizontal plane of the side 9 and the table 31. The parts having been pulled out and placed in the position shown in Fig. 1, and the typewriter having been used, a housing of the same within the pedestal is accomplished by lifting the outer free edge portion of the table until the support 15 may be turned upwardly, the table 31 with the attached typewriter 32 lowered to vertical position, and then by grasping the front metal plate handle 35 and pushing rearwardly, the table is moved along the rod or tube 30, receptacle 40 remaining stationary until the shoulder at 47 strikes the ear 44, whereupon said receptacle 40 and the table 31 are moved together inwardly into the pedestal. During this movement the roller 36 rides upon the track 24 until the rear vertical edge of the table 31 comes to the inclined cam face of the member 49, whereupon the lower part of the table 40 is swung inwardly to the position indicated in dotted lines in Fig. 6. This action occurs before the time that the front 8 is moved inwardly to a closed position. Therefore, when the typewriter is to be again used, initially necessitating the outward movement of the front 8 and side member 9, there is no bearing of the typewriter weight against the vertical side member 9 and no interference with the completely free outward movement thereof. This insures freedom and ease of movement of the parts, consisting of the front 8 with the attached legs 20 and the side member 9, to outer position and the turning of the legs downwardly to supporting position prior to any effect of the weight of the typewriter being transmitted to this supporting structure, which is initially withdrawn from the pedestal and moved outwardly and adjusted to supporting position, after which the typewriter table with the typewriter carried thereon and the other parts connected therewith are moved outwardly. It is, of course, to be understood that in housing the typewriter within the pedestal and then closing the same, after the typewriter and the receptacle 40 have been moved into the pedestal, the operating legs 20 are turned to the horizontal position of Fig. 4 prior to moving the front 8, with the connected vertical side member 9, to pedestal closing position.

70 It will be evident from the foregoing description that the construction of typewriter desk described very fully achieves the many objects and purposes described, provides in a two pedestal desk an over-all length not greater than the standard length of office desks now in use, which 75

is usually 54", and in a single pedestal typewriter desk provides a completely unbroken top which is usable either when the typewriter is out or is enclosed within the pedestal; and that the space underneath the typewriter in front of the stationery receptacle 40 and back of the back 8 is wholly unoccupied and unobstructed so as not to interfere with the operator of the typewriter in any respect. The support afforded by the legs 20 insures against any forward tipping tendency of even the small size typewriter desk.

It is to be understood that many variations in specific detail may be resorted to without departing from the invention. While the retractible supporting legs 20 are shown as hinged so as to be moved from an operative to an inoperative position and vice versa, the invention contemplates modifications wherein such legs could be moved bodily upwardly or downwardly to attain the same result so far as support for the lower end of the front 8 is concerned, this being a mere variation in mechanical detail. Other details of construction may be widely varied. Therefore, the invention is to be considered comprehensive of all forms of structure coming within the scope of the claims appended hereto, which claims define the invention.

I claim:

1. In a typewriter desk, a desk pedestal open at its front side, a vertical side member slidably mounted in said pedestal adjacent the outer side thereof, a front member permanently secured to the front end of said side member, a movable support mounted on said front member and adapted to be moved downwardly to engage with the floor or retracted upwardly, a table, an extensible track connected at its front end to said front member and its rear end connected to the pedestal, means for mounting said table on the track whereby the table is movable forwardly and rearwardly thereon and is swingable to a horizontal position, said table being adapted to have a typewriter carried thereon, and means for releasably supporting the table in horizontal position.

2. In a typewriter desk, a desk pedestal open at its front side, a vertical side member slidably mounted adjacent the outer side of the pedestal and adapted to be extended forwardly, a vertically positioned front member permanently secured at the front end of said side member and extending at right angles thereto adapted to close the pedestal when the side member is retracted therein, means for supporting said front member upon the floor below when it is extended, an extensible track having its front end secured to said front member and the rear end secured to the pedestal located in substantially parallel relation to said side member, a table, rollers carried at one side of said table and mounted on said track whereby the table may be moved outwardly over said track and turned into horizontal position with one edge portion thereof lying over the upper edge of said side member, said side member in its upper edge having recesses to receive said rollers, and means carried at the rear side of said front member for releasably supporting the table in horizontal position, as specified.

3. A construction containing the elements in combination defined in claim 2, combined with interengaging means on said vertical side member and table whereby said table is held against movement toward horizontal position until it has reached a predetermined outer position with reference to said vertical side member, thereby in-

suring that the said rollers will be positioned to enter said recesses in the vertical side member, the entrance of said rollers into said recesses locking the table against rearward movement on the track while the table is in horizontal position.

4. In a typewriter desk, a desk pedestal open at its front side, a vertical side member mounted in substantially parallel relation to and adjacent the outer side of the pedestal to have sliding movements into and out of said pedestal, a vertical front member permanently secured to the front end of said side member and extending at right angles thereto and adapted to close the front of the pedestal, legs hingedly connected at their upper ends to said front member at the rear side thereof and adapted to be turned to an upper horizontal position or downwardly to a vertical position, spring means acting on said legs tending to hold the same in either position to which moved, stops to limit the swinging movement of said legs to said horizontal and vertical positions, a horizontal tubular track member secured at its rear end to the pedestal and located in parallel relation to the outer side of the pedestal, a rod telescoping into the front end of said tubular track member and connected at its front end to said vertical front member, a table adapted to occupy a vertical position within the pedestal, rollers mounted on the outer side of said table and near the upper edge thereof riding on said tubular track member when the table is moved into the pedestal and upon said telescoping rod when moved outwardly, said table being swingable to a horizontal position when moved outwardly on said rod, means for releasably supporting the typewriter in horizontal position, said vertical side member having roller receiving recesses in its upper edge into which said rollers are received when the table is swung upwardly.

5. In a typewriter desk, a desk pedestal having an open front, a vertical front member for closing said open front, a vertical side member permanently secured to the rear side and outer edge portions of said front member, means for slidably mounting said side member for movement into and out of the pedestal, an extensible track connecting the back of the pedestal and the vertical front member, a typewriter carrying table mounted for bodily movement on said track into and out of the pedestal and for swinging movement upwardly to a horizontal position, means carried by said front member at its rear side for supporting the table in horizontal position, and movable supporting legs mounted on said front for engaging the floor to support the same and the weight of said table and typewriter, said movable legs being retractable to an upper position prior to moving said front into pedestal closing position.

6. In a typewriter desk, a desk pedestal open at its front side, a vertical side member slidably mounted in said pedestal adjacent a side thereof, a vertical front member permanently secured to the outer end of said side member and extending at right angles thereto, movable supporting means connected with the front member adapted to be moved to engage the floor after the side member and front have been moved to outer position, interengaging means on the pedestal and said side member tending to slightly elevate said front member during the movement of the same to its outermost position, a typewriter table adapted to occupy a vertical position within the pedestal, means for mounting the same for outward bodily movement and for an upward swinging movement

to horizontal position after said vertical side and front have been moved outwardly, means preventing said upward swinging movement until the table has reached a predetermined outer position, 5 and means carried by said front member for releasably supporting the table in horizontal position.

7. In a typewriter desk, a desk pedestal open at its front side, a vertical side member slidably mounted in said pedestal adjacent one side thereof, a front member permanently secured to the outer end of said side member and extending at right angles thereto, movable means adapted to be moved into position to engage the floor and support the front member after the same has been moved to its outmost position, a typewriter carrying table adapted to be located vertically when housed within the pedestal, means for mounting the same for outward movements to a position outside of the pedestal after the said vertical front and side member have been moved to outermost position, said mounting means for the table also permitting an upward swinging movement of the table to horizontal position after it is outside the pedestal, interengaging means on the table and vertical side member preventing movement of the table to horizontal position until it has reached a predetermined position with reference to said front member, and means carried by the front member for supporting the table in horizontal position.

8. A construction containing the elements in combination defined in claim 7, said means for mounting and carrying said table comprising, a telescoping tubular extensible track connected at its front end to said front member and at its rear end to the pedestal, and rollers carried by the table traversing said track.

9. A construction containing the elements in combination defined in claim 7, said means for mounting and carrying said table comprising, a telescoping tubular extensible track connected at its front end to said front member and at its rear end to the pedestal, rollers carried by the table traversing said track, a receptacle within said pedestal open at its front side, means for mounting said receptacle at one side and near its upper end on said track and at its opposite side on said pedestal, and connections between the table and receptacle whereby the receptacle is moved forward in the pedestal when the table is moved outwardly therefrom.

10. In a typewriter desk, a desk pedestal open at its front side, a vertical side member slidably mounted in said pedestal adjacent a side thereof, a front member secured to the outer end of said side member and located at right angles thereto, manually movable means connected to said front and adapted to be moved downwardly to engage the floor when said front has been moved to outer position, an extensible track connecting said front member and the pedestal substantially paralleling and located adjacent the upper edge of said side member, a typewriter carrying table, rollers thereon at one side riding on said track whereby the table in vertical position may be received within the pedestal, said rollers permitting swinging upward movement of the table to a horizontal position when moved outside of the pedestal, means for holding the table from movement to horizontal position until it has reached a predetermined outer position with reference to said front member, means for releasably supporting the table in horizontal position, a receptacle having an open front adapted

to be positioned in the rearmost part of the pedestal when the same is closed by the front member, means for mounting said receptacle for forward and rearward movements on the pedestal and on said track, a rod swivelly secured at its front end to the rear edge portion of the table, said rod having a head at its rear end, and an ear having an opening therethrough connected with said receptacle through which said rod slidably passes, whereby on forward movement of the table the rod slides through said ear for a distance and thereafter continued forward movement of the table moves the said receptacle forward therewith.

11. In a typewriter desk, a desk pedestal open at its front side, a vertical side member slidably mounted in said pedestal adjacent and parallel one side thereof, a vertical front member permanently secured to the forward end of said side member and positioned at right angles thereto to adapt to close the front of the pedestal when at inner position, a horizontal telescoping track connecting said vertical front member and the rear part of the pedestal, said track being located substantially parallel to and adjacent the upper edge of the vertical side member, a typewriter carrying table adapted to occupy a vertical position within the pedestal, rollers at the outer side of said vertically positioned table mounted on said telescoping track, a horizontal bar at the inner side of said vertical side member located adjacent the lower end of said table, a roller carried by said table to ride on the side of said bar, a cam member mounted within the pedestal in position to engage with the outer side and the rear part of the vertically positioned table when it is moved to innermost position within the pedestal, to move said last mentioned roller away from said bar, as specified.

12. In a typewriter desk, a desk pedestal having an open front, a vertical front member for closing said open front, a vertical side member permanently secured at the rear side and adjacent a vertical edge portion of said front member, means for slidably mounting said side member for movement into and out of the pedestal, an extensible track connecting the back of the pedestal and the vertical front member, a typewriter carrying table adapted to occupy a vertical position within the pedestal, rollers at one side of said table mounted on said extensible track whereby the table may be moved outwardly and be swung upwardly to a horizontal position when outside the pedestal, means carried by said front member at its rear side for supporting the table in horizontal position, and means carried by the table on the same side thereof as the rollers are mounted automatically engaging with said table supporting means and movable thereby into engagement with said track to bind said track between it and one of said rollers and thereby stabilize the table with reference to said track, as specified.

13. In a typewriter desk, a desk pedestal having an open front, a vertical front member for closing said open front of the pedestal, a vertical side member permanently secured to the rear side and at a vertical edge portion of said front member, means for slidably mounting said side member to move into and out of the pedestal, an extensible horizontal track connecting the back of the pedestal and front member, a typewriter carrying table mounted for bodily movement on said track into and out of the pedestal and for swinging movement upwardly to a horizontal

position, and means carried by said front member for supporting the table in horizontal position.

14. A construction containing the elements in combination defined in claim 13, said table having rollers thereon to traverse said track, a bar with inclined ends slidably mounted at the same side of the table as said rollers, with the track between one end of the bar and one of said rollers, the opposite end of said bar being positioned so as to engage the table supporting means when the table is held thereby in horizontal position to move the bar longitudinally and bring the end thereof adjacent said track into engagement with said track thereby locking the table against limited movements toward and away from said track.

15. In a typewriter desk, a desk pedestal having an open front, a vertical front member for closing said open front of the pedestal, a vertical side member permanently secured to the rear side and at a vertical edge portion of said front member, means for slidably mounting said side member for movement into and out of the pedestal, an extensible horizontal track connecting the back of the pedestal and the front member, a typewriter carrying table mounted on said track by means of rollers whereby said table may be moved into and out of the pedestal and may be swung upwardly to a horizontal position when in a position outside of the pedestal, means carried by said front member for supporting the table in horizontal position, and means for automatically stabilizing the table and rollers with reference to said track when the table is carried to horizontal position and engages with said table supporting means.

16. In a typewriter desk, a desk pedestal open at its front side, a side member slidably mounted within the opening of said pedestal, a front member secured to said side member, a table mounted on said side member and slideable with respect thereto whereby said table is movable into and out of said pedestal and is swingable to a horizontal position, and means for releasably supporting the table in a horizontal position.

17. A construction containing the elements in combination defined in claim 16, and means to prevent the upward swinging movement of said table until said table has reached a predetermined outward position.

18. The elements as defined in claim 16 and means for automatically stabilizing the table and rollers with reference to said side member when the table is carried to horizontal position and engages the said table supporting means.

19. The elements in combination as defined in claim 16 and means for preventing rearward movement of the table when in horizontal position.

20. The elements in combination as defined in claim 16 provided with interengaging means between the pedestal and said side member tending to slightly elevate said front member during the movement of the same to its outermost position.

21. The construction containing the elements in combination defined in claim 16, a receptacle within said pedestal open at its front side, means

for slidably mounting said receptacle for forward and rearward movement and connections between the table and receptacle whereby the receptacle is moved forward in the pedestal when the table is moved outwardly therefrom.

22. In a typewriter desk, a desk pedestal open at its front side, a vertical side member slidably mounted in said pedestal adjacent the side thereof, a front member permanently secured to the outer end of said side member and extending at right angles thereto, a typewriter table adapted to be located vertically and housed within the pedestal, means whereby the same is mounted for outward movement to a position outside the pedestal after the said vertical front and side members have been moved to outermost position, said mounting means for the table also permitting an upward turning movement of the table to horizontal position after it is outside the pedestal, and means carried by the front member for supporting the table in horizontal position.

23. A desk pedestal open at its front side, a side member slidably mounted in said pedestal, an extensible track connected at its front end to the front edge of said side member and at its rear end connected to the pedestal, a table, means whereby said table is mounted on the track whereby the table is movable forwardly and rearwardly thereon and is swingable to a horizontal position, and means for releasably supporting the table in horizontal position.

24. In a typewriter desk, a desk pedestal open at its front side, a side member slidably mounted in said pedestal adjacent the outer side thereof, a front member permanently secured to the front end of said side member, supporting means connecting said front member and said pedestal, a table, said table slidably and pivotally mounted on said supporting means whereby the table is movable within and out of said pedestal and is swingable to a horizontal position, means for releasably supporting the table in horizontal position, said table when in outer vertical position resting against the vertical side member, and means for moving said table from its resting position on the vertical side member when the table is moved within the pedestal.

25. In a typewriter desk, a desk pedestal open at its front side, a side member slidably mounted within said desk pedestal to move within and without of the pedestal, a front member permanently secured to the front end of said side member, an extensible track having its front end secured to said front member and the rear end secured to the pedestal and being located in substantially parallel relation to said side members, a table, rollers carried at one side of said table and mounted on said track whereby the table may be moved within or out of said pedestal and turned into horizontal position with one edge portion thereof lying over the upper edge of said side members, said side member at its upper edge having recesses to receive said rollers, and means carried at the rear side of said front member for releasably supporting the table in horizontal position.

JOHN H. BUSHNELL.
